This invention relates to improvements in the art of 15 actuating switches by means of accumulators.

For the connection of circuit breakers and power switches there are frequently used spring members which are tensioned by hand or by means of a motor. These members are held fast mechanically in a tensioned state by latches. These latches are released by the tripping control so that the shifting is effected by the disengagement of the accumulator. Such devices are provided, in the hitherto known constructions, separately for the connections and for the disconnections. This necessitates a 20 separate mechanism for the connection and disconnection operations. Said mechanism requires considerable space and complex arrangements. In addition, means are required for obtaining the correct sequence of the switches and the desired tensioning.

To reduce the number of these means, there are known 25 constructions in the prior art wherein the tensioning is effected by the switching process of the accumulator of the respective opposite switching operation. However, large dimensioning of the necessary accumulator springs is required in such cases since they must simultaneously switch and strain.

A practical simplification is now attained according to 30 the invention in that the connection and disconnection operations are effected by identical accumulators without any additional tensioning between switchings. According to the invention the accumulator works with a gear which is coupled with the driving shaft of the switch, which driving shaft rotates during the disengagement of the accumulator. In addition, the gear is combined with a pulling member, for example, a motor or a 35 crank, which tensions the accumulator. Both motions are performed independently of each other so that the tensioning member remains at rest during the switching operation and, inversely, the switch shaft remains in its respective position during the tensioning operation.

The number of the necessary details has been reduced 40 according to the present invention. Only one spring is required, which single spring is tensioned only once and then is available for connections and disconnections. In this case, it is also feasible to perform several switching series without any intermediate spring tensioning. Such gearings may also be used for the short interruption wherein a disconnection, a connection and, under certain 45 circumstances, again a disconnection must be performed within short intervals. To make this possible, there is utilized only a part of the entire spring lift for each switching. Accordingly, means must be provided for maintaining the gearing mechanism in intermediate 50 positions.

To make feasible the oppositely directed switching motions by the accumulator, moving in the same direction, there are required special gears. The construction of 55 these devices is more specifically explained in the following specification with reference to the appended drawings, in which:

2

Fig. 1 diagrammatically illustrates a simple embodiment of the invention;

Fig. 2 shows a modification of the embodiment illustrated in Fig. 1, in which an electric motor is employed 5 as driving member;

Fig. 3 illustrates the use of different latching means in the general organization of Fig. 2;

Fig. 4 illustrates the use, in the general organization, 10 of special means for providing a relatively great torsional moment for disconnection while a relatively smaller torsional moment is necessary for engagement.

Fig. 1 shows the connection of the accumulator or closing spring cylinder 1 with the gearing. As gearing there is, for example, represented a differential gear consisting of gear wheels, whereof the wheels, 3 and 4, are visible in the figure. The numeral 4 designates a gear wheel, rigidly connected with a driving member (member 21 in Fig. 2) and with a planetary pinion 3 rolling thereon. The latter is, through a lever 2, pivotally connected with the accumulator 1. When the accumulator is in the tensioned state, upon disengagement of the retaining mechanism, lever 2 will be rotated in a counter-clockwise direction. The pinion gear 3 rolls simultaneously on the gear 4.

Fig. 2 shows the connection with the driving shaft 6 and with a driving member 21, which is here indicated by an electric motor. A sprocket wheel 5 of a differential gear is rotated by the rolling planetary gear 3. Said gear wheel 5 is rigidly connected with the driving shaft 6 and indicates the double rate of revolutions of the rotary motion of the pinion gear. A switch 8 is, for example, actuated by the driving shaft 6 through a crank 7. When the crank moves upwardly, the switch thereby is connected; when it moves downwardly, the switch is moved to the "off" position. The switch angle on the crank amounts thus to 180°. In this embodiment, locking members 9a and 9b are disposed on the driving shaft 6. In the illustrated state, the left locking member 9a clamps the driving shaft. In order to effect the disconnection of this locking member, the respective stop latch 11a is lifted through the trip coil 10a. Then, the accumulator is released and rotates the driving shaft for a half revolution together with the switch until the right-hand locking member 9b is engaged. By this arrangement, 45 the sequence of the switching is always given positively so that no additional means are required.

The locking can be effected also in another way, as illustrated in Fig. 3. Instead of the locked levers 9a and 9b cam disks 12a and 12b are mounted on the driving shaft 6, which cam disks are held by rollers 14a and 14b seated on knee joint 13a and 13b. When the cams rotate, the roller 14a with the knee joint 13a is pushed down by cam disk 12a until at the lowest point it clamps the cam disk 12a and thus the driving shaft 6. The entire motion is damped by damping devices 15a and 15b, each of which may consist of piston and cylinder. The release is effected in that the knee joint 13a is, for example, magnetically released, as indicated by the arrow. The tensioning of the knee joint is effected by a spring 60 16a and a lever 17a. Similarly cam disk 12b, mounted on shaft 6 oppositely to disk 12a, actuates roller 14b and knee joint 13b.

During the disconnection, the accumulator spring reduces its force. Thus the torsional moment on the driving shaft differs according to the condition of the accumulator. This is generally permissible for smaller switches. In switches of great current intensity, this could show disadvantageous effects. Hence, it is preferred, according to the invention, to provide a special means whereby the magnitude of the torsional moment, affecting the switch through the driving shaft, is deliberately predetermined. To realize this, the point of ap-

plication of spring tension can be so displaced that the lever arm of the torsional moment becomes larger or smaller. It is possible to allow the lever arm of the torsional moment to become larger so that the torsional moment remains constant during the entire lift. Thus the lever may then be enlarged just for an amount corresponding to the diminution of the springiness due to the gradual disengagement. However, it can also be modified so as to produce a great torsional moment for the disconnection, while for the engagement a smaller torsional moment is produced since even the power consumption is smaller therefor. Hereby, the spring can be utilized to still better advantage.

A construction of this variable lever arm is shown in Fig. 4. Here is represented a cam plate 18, with the accumulator 1 acting thereon through a chain 19. The gear system 3, 4 which transmits the torsional moment to the driving shaft 6 is also represented. In the position designed, the accumulator 1 is tensioned. In this case the dimension of the effective lever arm on the cam plate is small (20). When the spring (accumulator) 1 is disconnected, the cam plate rotates along, whereby the effective lever arm is enlarged. By another shaping of the cam plate, the lever arm can be made smaller in an intermediate position so that a smaller torsional moment is available for the engagement than for the disengagement.

The accumulator may be driven either by hand or by a motor 21 (Fig. 2). According to the inventive idea, the motor needs to work always in the same rotating direction to lift the accumulator. If, for example, the motor fails, the switch must be lifted by hand, so that couplings must be provided for the existing constructions. According to the inventive object such discon-nectable couplings may be omitted. It appears necessary to combine only the manual drive through a stopping latch with the gear of the motor lift.

The inventive idea can, likewise, be applied to switches having several contacts which are engaged in various positions, e. g., stage-selector switches, through the use of eccentrics actuating the switch contacts, which eccen-trics are disposed on the driving shaft, the latter being driven through the differential gearing. Herewith several contacts can be actuated simultaneously or only one contact be actuated in each position of the driving shaft.
